Primary Examiner — Manpreet Matharu*Assistant Examiner* — Mojtaba Tehrani(74) *Attorney, Agent, or Firm* — Laurence A. Greenberg; Werner H. Stemmer; Ralph E. Locher(57) **CLAIM**

The ornamental design for a tire, as shown and described.

DESCRIPTION

FIG. 1 is a front view of the tire showing my new design, it being understood that the pattern repeats uniformly throughout the circumference of the tread;

FIG. 2 is a enlarged partial elevation view thereof;

FIG. 3 is a front perspective view thereof;

FIG. 4 is a left side elevation view thereof; and,

FIG. 5 is a right side elevation view thereof.

The broken lines form no part of the claimed design.
